CLAIM

The ornamental design for a device for dispensing a volatilizable substance, as shown and described.

DESCRIPTION

FIG. 1 is a perspective view of a device for dispensing a volatilizable substance according to the design; the back elevational view and side elevational views being the same; FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines depict portions of the device for dispensing a volatilizable substance that form no part of the claimed design.

1 Claim, 6 Drawing Sheets
